Primary Examiner — Darlington Ly(74) *Attorney, Agent, or Firm* — Alleman Hall McCoy Russell & Tuttle LLP(57) **CLAIM**

The ornamental design for a drill winch, as shown and described.

DESCRIPTION

FIG. 1 is a perspective view of a drill winch according to the present disclosure.

FIG. 2 is a front view of the drill winch of FIG. 1.

FIG. 3 is a back view of the drill winch of FIG. 1.

FIG. 4 is a left view of the drill winch of FIG. 1.

FIG. 5 is a right view of the drill winch of FIG. 1.

FIG. 6 is a top view of the drill winch of FIG. 1; and,

FIG. 7 is a bottom view of the drill winch of FIG. 1.

The broken lines in the drawings illustrate portions of the drill winch that forms no part of the claimed design.

1 Claim, 7 Drawing Sheets(56)
